UNITED STATES PATENT OFFICE.

PERCY F. RICE, OF TUSTIN, CALIFORNIA, ASSIGNOR OF ONE-THIRD TO EARL V. LEWIS AND ONE-SIXTH TO W. H. FAUST, BOTH, OF LOS ANGELES, CALIFORNIA.

MEANS FOR PREVENTING DOUBLE EXPOSURES.

No. 903,405.

Specification of Letters Patent. Patented Nov. 10, 1908.

Application filed September 5, 1907. Serial No. 391,443.

To all whom it may concern:

Be it known that I, PERCY F. RICE, a citizen of the United States, residing at Tustin, in the county of Los Angeles and State of California, have invented a new and useful Means for Preventing Double Exposures, of which the following is a specification.

This invention relates to cameras and particularly to a device for preventing double exposures, the object of the invention being to provide a simple means whereby after the film has been exposed the shutter cannot be operated again to expose the film a second time until after the film has been turned.

Another object is to provide a device of this character which may be applied to a camera of the folding type.

The accompanying drawings illustrate the invention, and referring thereto:—Figure 1 is a front elevation of a camera equipped with this invention. Fig. 2 is an enlarged detail view, in section, on line x^2-x^2 Fig. 1, showing the parts in normal position. Fig. 3 is a view similar to Fig. 2, showing the parts in the position which they have immediately after the bulb has been pressed and prior to the relaxation of the bulb. Fig. 4 is a view similar to Fig. 2, showing the position of the parts immediately after the bulb has been relaxed.

1 designates the case of the camera having the front folding table 2 provided with a way 3 upon which head 7 is slidably mounted, the head 7 being equipped with lens 8 and a shutter case 9, the shutter mechanism being operated by a lever 10 and the latter may be either manipulated by hand or by means of a pneumatic device comprising a cylinder 11 carrying a plunger 12, air being forced into the cylinder 11, below the plunger 12, by means of a rubber bulb 13 which communicates through a tube 14 with the lower end of cylinder 11. By squeezing bulb 13 air is forced into the cylinder 11 to lift plunger 12 and operate shutter lever 10 in the well known manner.

In carrying out my invention I prefer to operate the same pneumatically, the particular mode of operation being to allow the plunger 12 to be raised by air pressure to open and close the shutter once, but to prevent the plunger 12 from being operated a second time until the roll of film has been turned.

15 designates the film spool upon which

the roll of film is wound, the film spool being detachably connected with a ratchet 16, the ratchet 16 being operated by thumb piece 17. All these parts are well known in the art and do not need further description. Fixed to the case 1 is a cylinder 18 shown in dotted lines in Fig. 1, and in section in Figs. 2, 3 and 4. The cylinder 18 has an end nipple 19 which is connected by a flexible tube 20 with a nipple 21 formed on the lower end of cylinder 11. Slidable within the cylinder 18 is an intermediate cylinder 22 having a closed outer end with a reduced diameter 23 forming an annular air space 24, there being a stud 25 on its end. The reduced end 23 is provided with ports 26. Within the intermediate cylinder 22 is a plunger 27, the inner end of which is open. The plunger 27 is provided with lateral ports 28 which are adapted to register with ports 26 of the intermediate cylinder as will be explained. A helical spring 30 is arranged between the end of the plunger 27 and the head of the intermediate cylinder 22. The stud 25 bears against a flat spring 32, the latter being secured to the side framework of the case 1. The spring 32 has a lateral arm 33 formed with a detent 34 on its end which is adapted to be engaged with ratchet 16 before referred to.

In the operation of the device, just before operating the shutter to make an exposure, the parts stand in the relative positions shown in Fig. 2, with the ports 28 out of register with ports 26, the plunger 27 being retracted, and the intermediate cylinder 22 retracted, and the detent 34 of spring 33 being out of engagement with ratchet 16, the spring 30 being compressed as the intermediate cylinder is held back by the stronger spring 32. By pressing bulb 13 air is forced into the cylinder 11 which lifts the plunger 12 and acts upon lever 10 to open and close the shutter, the shutter being set for instantaneous exposures; at the same time the air is forced through the tube 20 into cylinder 18 into the interior of plunger 27 and as none of this air can escape it forces the intermediate cylinder 22 and plunger 27 to the right, both moving as one piece, and as the stud 25 presses forward spring 32 it causes detent 34 to engage with a tooth of the ratchet 16 and the parts take the position shown in Fig. 3. The ports 26 and 28 are still out of register and air can-

not escape and so long as this air pressure is maintained inside of plunger 27 the spring 30 is kept compressed. When the hand of the operator allows bulb 13 to relax the air pressure within plunger 27 reduces, whereupon the spring 30 expands and moves the plunger 27 to the left, bringing ports 28 into register with ports 26, the intermediate cylinder 22 at this time not retracting as the spring 33 exerts no pressure against it, the spring 33 being retained by the ratchet, and cylinder 22 is held in contact against spring 32 by the reactive pressure of spring 30. It should be understood that the tension of spring 33 which is hooked to the ratchet is not sufficient to turn the ratchet on account of the considerable relative power required to turn the ratchet due to friction and film resistance. The parts thus take the position shown in Fig. 4. It should be understood that the parts attain the position shown in Fig. 4 practically instantaneously upon release of the pressure of bulb 13 as the cylinder 22 and plunger 27 have a very slight movement, in fact having even less movement than the plunger 12.

It will now be observed that when the parts are in the position shown in Fig. 4, if the bulb 13 be pressed in the attempt to expose the film a second time that the air compressed by bulb 13 will not be effective against plunger 12 as this air will escape through tube 20 into plunger 27 and through ports 28 and 26 into annular space 24, and thence out into the atmosphere. In such operation of bulb 13 the operator at once notices the nonresistance of bulb 13, and also notices that the shutter does not operate, which indicates to him that he has neglected to turn a fresh film into place. Even though this fact is not noticed by the operator it is impossible for him to operate the shutter by means of bulb 13 and produce a double exposure, as every time the bulb 13 is pressed the air exhausts without operating plunger 12. The operator then turns the film spool 15 to bring another film into position which operates ratchet 16 clockwise, which is its only direction of movement, and this movement of the ratchet allows spring 33 to retract, and the detent 34 then disengages from ratchet 16 and the spring 33 in its retraction moves back cylinder 22 to normal position compressing spring 30 and moving ports 26 out of register with ports 28, at which time the parts have again taken the position shown in Fig. 2, and the device is now in a position such that upon pressing bulb 13 the air will not be allowed to escape but will operate plunger 12 to work the shutter.

It will be noted that tube 20 permits of the focusing movement of the lens so that the device is operative in any position of the lens.

It should also be noted that this device will operate when the shutter is set for "bulb" operation instead of "instantaneous", although in operating under the "bulb" the relaxation of the bulb may take place with more delay than under "instantaneous".

It is obvious that when the shutter is adjusted to "bulb" that, inasmuch as the air pressure is not reduced until the bulb is relaxed by the hand, that the time interval between the positions shown in Figs. 3 and 4 will be greater than when the shutter is set for "instantaneous", this time interval corresponding to the period that the bulb is held closed by the hand and the shutter open.

In operating when the shutter is set for a "time" exposure wherein two successive pressures of the bulb are required to open the shutter and close it the device also will operate, contrary to what would be casually apparent, for the reason that in a time exposure the second pressure on the bulb need be very slight compared to the first as is well known because the first pressure must be strong to furnish the power to set the shutter open, while the second pressure need only furnish the small power required to release the shutter, the power for the opening and closing movements of the shutter having been provided by the first pressure. Thus in a time exposure, after the second pressure, although the ports are in register and air can escape, its escape is restricted sufficiently to cause the necessary slight pressure to build up to close the shutter, but as this slight pressure is very much less than that required for the opening movement of the shutter the device when working under "instantaneous" or "bulb" prevents the second exposure.

What I claim is:—

1. In a device for preventing double exposures, a shutter, means for operating the shutter, a film operating device, and pneumatic means intermediate the film operating device and the shutter operating means for controlling the shutter, the said pneumatic means being operable by the film operating device.

2. In a device for preventing double exposures, a shutter, pneumatic means for operating the shutter, a film operating device, and means controlled by the film operating device for allowing or preventing air to escape from the pneumatic shutter operating means.

3. In a device for preventing double exposures, a shutter, pneumatic means for operating the shutter, a film operating device, a plurality of telescoping cylinders having ports, a tube for conveying air from the shutter operating means to said tubes, and means coacting with the film operating

means for controlling the relative position of said cylinders and their ports whereby air is allowed to escape or is prevented from escaping from said cylinders.

5. 4. In a device for preventing double exposures, a film operating device including a ratchet, a spring adapted to engage the ratchet, a stationary cylinder, an intermediate cylinder slidable in the stationary cylinder and having exhaust ports and bearing against said spring, a hollow plunger within 10 the intermediate cylinder having exhaust

ports, a helical spring between the plunger and intermediate cylinder, a shutter, a cylinder and plunger for operating the shutter, and a tube extending from the latter cylinder to the first cylinder. 15

In testimony whereof, I have hereunto set my hand at Los Angeles, California, this 29th day of August 1907.

PERCY F. RICE.
